UNITED STATES PATENT OFFICE.

ERICH BANDOLY, OF CHICAGO, ILLINOIS, ASSIGNOR TO CENTRAL SCIENTIFIC COMPANY, OF CHICAGO, ILLINOIS, A CORPORATION OF ILLINOIS.

VACUUM PUMP.

Application filed April 9, 1926. Serial No. 100,801.

This invention relates to an apparatus for producing high vacua in which the pump element is sealed with oil; when the pump is stopped for any considerable period, atmospheric pressure forces oil through the pump toward, or into, the vacuum system. The principal object of this invention is to provide a trap for intercepting this fugitive oil.

Further objects of the invention are to provide improved means for operating the blades of the eccentric pumps, to produce a simple compact piece of apparatus that can be readily manufactured at small cost and easily handled in the laboratory, and to generally improve the character of apparatus used for this purpose.

The preferred embodiment of the invention is illustrated in the accompanying drawings in which

Fig. 1 is a sectional view through an eccentric pump and oil bath taken along the axis of the driving shaft;

Fig. 2 is a similar section taken on the line 2—2 of Fig. 1;

Fig. 3 is a section of the oil trap taken on the line 3—3 of Fig. 1;

Fig. 4 is an elevation of the inside face of the removable wall of the oil bath casing, and

Fig. 5 is a view similar to Fig. 1, illustrating a modified construction of oil trap and oil bath.

But these specific illustrations and corresponding specific descriptions are used to make the invention clear and are not intended to require a limitation of the claims other than is made necessary by the prior art.

The apparatus illustrated includes an oil bath generally indicated by A and an eccentric pump generally indicated by B and mounted in the bath.

The pump is of the eccentric type including two units, each composed of a cylinder 10, an eccentric rotor 11, driven by a shaft 12 mounted concentric with the cylinder and a blade 13 (Fig. 2) reciprocating in a slot 14 in the cylinder wall and contacting with the outer surface of the rotor 11. The ends of the cylinders are closed by plates 15, 16 and 17.

The walls of the cylinders 10 are extended laterally, as indicated at 18, in the neighborhood of the slots 14, and the plates 15 and 16 having corresponding extensions to cover the side portions of the slots and make working contact with the blades 13.

The plate 16 is equipped with ears 19 and

20, each having laterally extending pins 21 connected with one end of a tensile spring 22, the other end of which is connected with one arm 23 of the bell crank lever fulcrumed at 24 on the plate 16 and having another arm 25 resting upon the outer end of the corresponding blade 13. This mechanism will serve to maintain the inner end of each blade in intimate contact with the peripheral surface 26 of the corresponding rotor 11.

Each rotor has a relatively long zone of contact with the inner surface of its cylinder, as indicated at 27 in Fig. 2. The periphery of the cylinder is equipped with an inlet passage 28 and an outlet passage 29 entering the cylinder at a distance not greater than the zone 27. The outlet passage is normally closed by a flap valve 30 and the inlet passage is connected with the vessel to be exhausted.

In order to facilitate the assembly of the pump with the bath and the support of the pump therein one wall 31 (Fig. 1) of the bath casing is made readily removable and equipped with fastenings for securing the pump to it. The remainder of the bath casing is made in one piece comprising a bottom 32 and sides 33, 34 and 35, each side having an inturned flange 36 which, together are adapted to receive a removable cover 37.

The upper portion of the removable wall is formed hollow to provide a trap chamber 38 which is connected with the inlet passage 28 at the bottom and equipped with a hose nipple 39 by which the pump may be connected with the vessel to be exhausted.

In the form shown in Fig. 1 the bath is made of aluminum die casting and the chamber 38 is provided with a lining shell of steel composed of a cup-shaped element 40, a disk 41 closing its open side, and a reenforcing strut 42 bent back and forth as indicated in Fig. 3, and lying between the opposite sides of the chamber. A short piece of steel tubing 43 extends from the inner side of the chamber to the outer face of the plate 15. A sealing cup 44 has a shouldered neck 45 extending through the lining and the aluminum and threaded to receive the hose nipple 39.

In practice, the reenforcement is welded at a few points to the disk 41 and the disk 41 is welded to the rim of the cup 40, the tubing 43 and the sealing cup 44 are welded to the disk and the cup in the position shown. This assembly forms an insert which is placed in

the molding die and about which the jacket of aluminum, zinc, alloy, or other light metal is cast.

The steel liner makes the trap mercury proof and in the majority of cases will make it also air tight. However, to insure uniformly air tight structures in production the pores should be sealed, which may be accomplished in the following manner.

10. Plug the tubing; screw the cups 44 onto the nipples of a manifold connected with a vacuum pump; exhaust the trap chambers and submerge the castings in a sealing material normally solid, but temporarily rendered liquid, such as, for example, japan; continue the submerging until the atmospheric pressure has had an ample opportunity to force the japan into the minute pores; remove and bake to solidify the japan; immerse again 20 without exhausting and bake the second time.

The lower portion of the removable wall 31 is thin and solid as indicated at 46, and equipped with a marginal flange 47 terminating in alignment with the inner face of the 25 upper portion, this face 48 and the corresponding face of the flange 47 are ground to cooperate with the ground face 49 of the plate 15 to form a proper joint.

The plate 15 is extended beyond the margins of the cylinder 10, as indicated at 50, (Fig. 2) and drilled and tapped to receive 30 studs 51 by which the pump is secured to the wall 31, the latter being thickened at 52 and 53 and drilled and tapped to receive the studs.

35. The removable wall is also thickened and drilled at 54 to receive studs which thread into tapped openings in the body of the bath and secure the removable wall in place.

The lower portion 46 of the wall 31 is provided with a boss 55 aligned with a brass insert 56 which, together with the gland 57 and packing 58, forms a stuffing box for the shaft 12.

When the bath is made of cast iron the removable wall 60 (Fig. 5) is formed with a trap chamber 61 without any lining, corresponding to that shown in Figs. 1 and 3. Any pores in the walls of this chamber may be sealed by the procedure described above.

50. I claim as my invention:

1. In apparatus of the class described, the combination of an oil bath including a casing, a pump within the bath and an inlet passage leading from the pump through the casing and adapted to be connected with the vessel to be exhausted, said inlet passage being enlarged within the casing to form an oil trap.

2. In apparatus of the class described, the combination of an oil bath including a casing having one side removable and formed with a relatively large chamber therein, a pump within said oil bath, an inlet passage for the pump including a connection between the chamber and the pump and a connection

between the chamber and the vessel to be exhausted.

3. In apparatus of the class described, the combination of a pump including a cylinder, an eccentric rotor in the cylinder, an oil bath 70 for the pump including a casing having a wall formed hollow above the rotor, a passage connecting the cylinder with the hollow of the wall and means for connecting the hollow of the wall with the vessel to be exhausted. 75

4. In apparatus of the class described, the combination of a pump including a cylinder, a rotor within the cylinder, a shaft driving the rotor, an oil bath for the pump including 80 a wall having a chamber formed in its upper portion, an inlet passage for the pump connected with the chamber in the wall, a stuffing box for the shaft in the wall below the chamber and an oil cavity in the wall surrounding the stuffing box and communicating with the bath. 85

5. In an oil bath for pumps, a casing made in two parts, the first part including a bottom and walls for three sides, the second part 90 including a wall for the remaining side and adapted to be secured to the first part, said second part having an oil trap formed in its upper portion and adapted to be connected with the pump and with the vessel to be exhausted. 95

6. In an oil sealed exhaust pump, an oil trap comprising a shell of wrought metal and a sheet of cast metal enclosing the shell and in the condition of having been cast thereon. 100

7. In an oil sealed exhaust pump, an oil trap including a shell of steel and an enclosing casing of light metal cast about the shell.

8. An oil sealed exhaust pump, comprising an aluminum die casting having a hollow 105 therein and a lining of non-porous wrought metal for said hollow.

9. An oil sealed exhaust pump, comprising a hollow light metal die casting lined with ferrous wrought metal. 110

10. In a pump of the character described, the combination of a cylinder, an eccentric rotor mounted therein, a blade slideable through the wall of the cylinder and making contact with the surface of the rotor, a pivoted lever resting on the outer end of the blade and a helical tension spring spaced from the pivot of the lever and constantly urging it against the blade. 115

11. In a pump of the character described, 120 the combination of a cylinder, an eccentric rotor mounted therein, a blade slideable through the wall of the cylinder and means for holding the inner end of the blade in contact with the eccentric surface of the rotor, comprising a bent lever having one arm operatively connected with the outer end of the blade and a helical tension spring spaced from the bend of the lever and constantly 125 acting upon the other arm. 130

12. In a pump of the class described, the combination of a cylinder, an eccentric rotor mounted therein, a blade slidably mounted in the wall of the cylinder, and means for urging the blade into contact with the eccentric surface of the rotor comprising a tension spring, a bell crank lever having one arm connected with the spring and the other arm operatively connected with the plate.
13. In a device of the class described, a wall section comprising a hollow upper portion and a thin flat lower portion in line with the outer wall of the upper portion and having a marginal flange extending inwardly to a point approximately in line with the inner wall of the hollow portion, and a boss projecting inwardly from the flat portion for receiving a stuffing box.
14. In an oil bath for pumps of the class described, a casting forming a wall thereof and comprising a thin wall below encircled by an inwardly projecting marginal flange and a double wall above providing a trap for oil.
15. In an apparatus of the class described, the combination of an oil bath including a casing having one removable side wall, a pump attached to the removable side wall and located in the bath, said pump having an inlet passage extending through the removable side wall and being enlarged above the pump to form an oil trap.
16. In apparatus of the class described, an oil trap comprising a shell of non-porous metal, and a casing of porous metal including the shell and in the condition of having been cast about the same.
17. In an apparatus of the class described, an oil trap formed of metal having its pores occupied by material impervious to fluids.
18. An apparatus of the class described, the combination of an oil bath, a pump therein having an inlet passage and an oil trap for the inlet passage including a hollow casting of metal having its pores occupied by material impervious to fluids.

In testimony whereof I affix my signature.
ERICH BANDOLY.
